JOHN H. LONDICK, OF PORTSMOUTH, OHIO, ASSIGNOR OF ONE-THIRD TO ALBERT J. STEELE, OF NORTH BALTIMORE, OHIO.

ENGINE-STARTER.

1,121,108.

Specification of Letters Patent. Patented Dec. 15, 1914.

Application filed February 10, 1913, Serial No. 747,407. Renewed July 24, 1914. Serial No. 852,937.

To all whom it may concern:

Be it known that I, JOHN H. LONDICK, a citizen of the United States, and a resident of Portsmouth, in the county of Scioto and 5 State of Ohio, have invented a certain new and useful Engine-Start; and I do hereby declare the following to be a full, clear, and exact description of the invention, such as will enable others skilled in the art to which 10 it appertains to make and use the same, reference being had to the accompanying drawings, and to the characters of reference marked thereon, which form a part of this specification.

15 This invention relates particularly to spring starting apparatus for internal combustion engines, but is not restricted to such use as it may be employed in any connection for which it may be adapted or appropriate.

20 The object of my invention is the provision of a starting apparatus of this character, which is simple, and compact in its construction and provided with improved means for controlling the release of a shaft 25 driving spring and the rewinding thereof, whereby to enhance the practicability and commercial value of apparatus of this character.

A further object of the invention is the 30 provision, in an apparatus of this class, of a plurality of energy storing springs, which are independently operable in predetermined order to impart turning movements to the associated engine shaft, whereby one 35 or more of the springs of a set can be employed for starting as the starting of the engine may require, thus obviating the necessity of rewinding a spring by hand if the energy stored therein is not sufficient to start 40 the engine.

A further object of the invention is the provision, in a multiple independently-operable spring starter of this class, of improved means which is automatically operable to 45 rewind an unwound spring or springs of the set when the engine shaft is being turned by the running of the engine.

The invention is fully described in the following specification, and while, in its 50 broader aspect, it is capable of embodiment in numerous forms, a preferred embodiment thereof is illustrated in the accompanying drawings, in which,—

Figure 1 is a side elevation of an apparatus embodying the invention with a por-

tion of the same in central vertical section. Fig. 2 is a right-hand end elevation thereof with parts broken away. Fig. 3 is a cross-section on the line α , α in Fig. 1. Figs. 4 and 5 are side and end views of the control shaft for the several spring units. Fig. 6 is a detail of the clutch connection between the two sections of the engine shaft. Figs. 7 and 8 are different details of the trip finger of the apparatus, and Fig. 9 is a side elevation of a portion of the body of an automobile equipped with the invention, with parts broken away.

Referring to the drawings, 1 designates the crank-shaft of an engine, and 2 an axially alining longitudinally shiftable extension for the outer or forward end of said shaft, said section being adapted to have clutch engagement at its inner end with the adjacent end of the shaft 1, as indicated at 3 in Fig. 6. A shift collar 4 is mounted over the adjacent ends of the two shaft sections 1 and 2, being feathered, in the present instance, to the shaft section 1, as indicated at 5, and having pin-and-groove connection 70 with the shaft section 2, as shown at 6, to admit of an axial shifting of the collar to move the shaft section 2 into or out of clutch engagement with the shaft section 1.

The shaft section 2 carries the casing 7 of 85 the starter apparatus and projects through and is journaled in a plurality of spaced partition members 8, which are disposed in the casing transversely thereof and divide the same into a plurality of compartments 9. 90 In each of these compartments is mounted one of the starter units of the apparatus, and as such units are of duplicate construction a detailed description of one only thereof will be given.

95 Each starter unit has a hub member or collar 10 encircling the shaft section 2 within its compartment 9 and loosely mounted, in the present instance, at its opposite ends on extensions of the bearing portions 8' of 10 the adjacent partitions 8 of the compartments, and has the portion thereof intermediate said bearing parts formed with tapered race-ways 12 (see Fig. 3) in which clutch rollers 13 work to coöperate with said 10 collar to clutch the shaft to cause the collar, when rotated in one direction, to effect a driving of the shaft. Loosely mounted on the right-hand end portion of the clutch collar 10, in the present instance, is a disk 11

14, which is provided at its outer edge with an annular transversely projecting flange 14', which projects over the collar 10 and forms a drum for inclosing the associated 5 starter spring 15, which is spirally wound around the collar 10 and has its outer end fixedly attached to the flange 14', as at 16, and its inner end fixedly attached to the collar 10, as at 17.

10 The clutch collar 10 is normally prevented from turning under the influence of the spring 15, when the latter has energy stored therein, by a catch-member 18, which is pivoted to a stud 19 projecting from the 15 partition 8 adjacent to the open side of the spring carrying shell 14-14' and has its free end provided with a catch-nose for engaging a lug 20 on the collar 10, as best shown in Fig. 3. An arm 21 is pivotally attached to the catch end of the member 18 20 and extends upward therefrom and is provided at its upper end with a forked yoke 22 through which a trip-shaft 23 loosely 25 passes. This shaft extends throughout the length of the casing 7, being journaled in the partitions 8 and has a cam-lug or spur 24 projecting radially of the yoke 22. A cam-lug 24 at each revolution of the shaft 23 engages a registering pin 25 within the 30 yoke to move the arm 21 to effect an upward raising of the catch-member 18 from locking engagement with the collar-lug 20, the yoke opening, through which the shaft passes, being vertically elongated for such 35 purpose. If four starting units are provided, as in the present case, the lugs 24 on the shaft 23 are disposed at different quarters of the shaft so that upon a complete 40 turning of the shaft 23 the clutch collars 10 of the different units will be successively released at different quarter turns of the shaft in the order of successive circular arrangement of the lugs on the shaft.

The trip-shaft 23 has intermittent quarterly turns imparted thereto by oscillatory movements of the ratchet-arm 26, that is mounted on the inner end thereof without the case 7, and has connection with any suitable control means. The control means, 50 in the present instance, is shown as comprising a foot treadle 27 (see Fig. 9) the lower end of which is connected by a rod 28 to a swinging link 29 attached to the under side of the forward end portion of 55 the automobile frame, and this link is connected by a link 30 to a link 31, which in turn attaches to the ratchet-arm 26. The connection between the foot-treadle 27 and ratchet-arm 26 is preferably such that a depression of the foot-treadle will communicate a quarter turning movement to the trip-shaft.

The shift-collar 4 on the engine shaft has connection with the links 30 and 31, at their 65 points of pivotal connection, by a shift lever

32, which is carried by a bracket-arm 33 projecting from the adjacent end of the case 7 and is adapted to shift the collar 4 to effect a movement of the shaft section 2 into clutch engagement with the shaft section 1 when the links 30 and 31 are moved to impart a tripping movement to the shaft 23. It is thus apparent that the shaft-sections 1 and 2 are in engagement when the clutch-collar 10 is released so that the turning movement which is imparted to the section 2 by the released spring will immediately be communicated to the section 1 to start the associated engine. The collar 4 and other control parts are normally maintained in the position shown in Fig. 1, with the shaft sections disconnected, in any suitable manner, as by a spring 27^a, which connects the treadle 27 to an adjacent frame part and yieldingly resists a depressing of the treadle.

Mounted preferably in the lower portion of the case 7 throughout the length thereof in suitable bearings provided in the partitions 8 is a countershaft 34, which carries 90 a loose-gear 35 in each compartment 9 in mesh with a gear 36 on the outer side of the associated spring carrying part 14. The shaft 34 also carries a clutch-member 37 within each compartment of the case for 95 shifting movements into or out of clutch engagement with a complementary portion of the associated gear 35, the said member being splined or feathered to the shaft in any suitable manner and normally held disengaged from the gear by a spring 38. A collar 39 is loosely mounted on the shaft 34 between the outer end of the clutch-member 37, and the adjacent partition 8, and the partition and collar have complementary 105 cam-surfaces, as at 40, which cause the collar when partially rotated on the shaft to have an axial movement to impart a gear engaging movement to the clutch-member 37, as is apparent.

The collar 39 has an arm 41 projecting radially therefrom, and pivoted to the outer end of this arm is a thrust-finger 42, which projects transversely from said arm, as shown in Fig. 3, for the purpose hereinafter 110 described. A pin 43 projects from the adjacent partition 8 through a longitudinal slot 44 in the finger 42 to guide the movements thereof. A coiled contraction spring 45 is attached at one end to the finger 42 and at 115 its other end to the interior of the case 7 (see Fig. 3) to influence a movement of the finger and arm 39 in a direction to move the complementary cam surfaces 40 out of register and to force the clutch member 37 into engagement with its clutch gear, so that a driving of the shaft 34 will effect a 120 turning of the spring carrying drum 14-14' through the medium of the gears 35 and 36 to rewind the associated spring 15 when its 125 130

energy has been spent. A spring finger 46 is attached at one end to the inner side of the drum flange 14', with its free end projecting in the direction of spring winding rotation 5 of said flange, and normally tending to move inward relative to the flange. When the spring is in its wound or contracted state the laterally projecting nose 46' on the free end portion of the spring-finger 46 coacts with 10 the free end of the thrust-finger 42 to hold such finger and connected collar 39 in neutral or clutch released position against the tension of the spring 45. When the spring 15 expands upon an unwinding movement thereof 15 of, the spring-finger 46 is forced outward thereby from end thrust engagement with the thrust-finger 42, thus permitting such finger and attached parts to move to clutch engaging position under the influence of the 20 spring 45, whereby to throw the spring rewinding mechanism into operation. As the spring drum 14-14' rotates upon a rewinding of the spring 15 the spring-finger 46 revolves therewith until the spring has been 25 contracted a sufficient extent to permit the nose 46' of the spring-finger 46 to move into engagement with the registering end of the thrust-finger 42, when such fingers will coact to move the collar 15 to neutral position 30 to permit a release of the clutch member 37 from engagement with its gear, thus stopping a further winding of the spring. The nose or outer end portion of the thrust-finger 42 is laterally offset to provide a 35 thrust surface for the nose 46' of the spring-finger 46 and to enable the nose 46' to pass under the coacting end portion of the finger 42 when the path of movement of the nose portion of the spring-finger is without the 40 offset portion of the thrust-finger.

The means employed for communicating rotary movements to the shaft 34 from the engine shaft consists, in the present instance, of an eccentric 47 that is loosely mounted 45 on the shaft section 2 at the rear end of the case 7 and has connection through an eccentric strap and arm 48 with a ratchet arm 49 on the rear end of the shaft 34, whereby the movements imparted to the arm 48, during a rotation of the eccentric 47, will communicate an intermittent rotary movement 50 to the shaft 34. The eccentric 47 is driven from the shaft section 1 when the engine is running and the shaft sections 1 and 2 are disconnected, due to the shift collar 4, when in normal position, having its forward end in clutch engagement with the eccentric collar, as at 50, and having its rear end splined 55 to the shaft section 1, as shown in Figs. 1 and 6. It is thus evident that the springs 15 can only be rewound when the shiftable control parts are in their normal position with the shaft sections disengaged.

60 A pawl 51 is carried by the case 7 for each gear 36, and is adapted to engage the teeth

thereof in a manner to prevent a back turning or spring unwinding movement of the drum 14-14', as shown in Fig. 2.

In order to effect a positive return of the catch-member 18 to engagement with the lug 20 on the clutch-collar 10 after the associated spring 15 has spent its force in turning the engine shaft or until the rewinding action occurs, the member 18 is provided at its inner end with an upwardly projecting 75 arm 18^a, which has a spring finger or brush 18^b projecting from its outer end in contiguous relation to the flange 14' of the spring drum in position to be engaged by the free end of the spring-finger 46 upon a revolution 80 thereof with the drum. The spring-finger 46 engages the spring finger 18^b in a direction to rock the catch member 18 into engagement with the clutch-lug 20.

The operation of my improved starter 85 apparatus is as follows: To start an engine the operator depresses the foot-treadle 27 to communicate a rocking movement to the ratchet-arm 26 on the tripshaft 23 and also to rock the lever 32 to shift the sleeve 4 longitudinally of the engine shaft to release its clutch engagement with the eccentric 47, and to move the shaft section 2 rearward into clutch engagement with the shaft section 1. The movement of the ratchet-arm 90 26 is sufficient to impart a quarter turn to the trip-shaft 23, should the starter be of the four unit type, and moves one of the trip-lugs 24 on such shaft to effect a raising movement of the associated arm 21 due to 100 the coaction of the lug with a pin 25 at the yoke end of such arm. The raising of the arm 21 retracts the catch-member 18 from engagement with the lug 20 on the associated clutch-collar 10, and permits such 105 collar to rapidly turn under the influence of the spring 15 and to communicate rotation to the engine shaft due to the clutch engagement of the collar 10 and rollers 13 therewith. Should the starting action of the 110 spring 15 of one of the starter units be insufficient to start the motor, the operator releases the foot-treadle 27 to permit the ratchet arm 26 to return to its normal position, and then again depresses the foot-treadle to impart another quarter turn to the trip-shaft 23 to effect a release of the 115 spring of the next unit in order, which release is effected in the same manner as described for the first spring. This releasing 120 action may be repeated for the several units of a set if desired. The expanding or unwinding action of each starter-spring 15 moves the free end of the spring finger 46 outward from end thrust engagement with the thrust finger 42 to permit such finger and the connected cam member 39 to move under the influence of the spring 45 to throw the clutch collar 37 on the rewinding shaft 34 into clutch engagement with the gear 35 130

to place the rewinding parts in condition to rewind the released springs 15 when the shaft 34 is driven for such purpose. When the motor has been started and the engine shaft is running, the foot-treadle 27 is released to permit the shift-sleeve 4 to return to its normal position with its forward end in clutch engagement with the eccentric 47, whereby the shaft section 2 is released from the section 1 and the eccentric 47 is driven from the section 1. The driving of the eccentric 47 by the motor communicates rotation to the rewinding-shaft 34 and causes a rewinding of the spring or springs, which were released in the starting action, by reason of the gears 35 being in mesh with the drum-gears 36 and being in clutch connection with the shaft 34, as above described. When a starter spring has been rewound a predetermined extent the free end of the associated spring-finger 46, which revolves with the drum 14-14' during the rewinding action, will have moved inward with the outer convolution of the spring sufficiently for the nose 46' thereof to have end-thrust contact with the thrust-finger 42, whereby to effect a movement of the finger 42 against the tension of the spring 45 to throw the cam-member 39 to its neutral position and to permit a releasing of the associated clutch-collar 37 from engagement with its gear 35, thus stopping the rewinding action.

It is evident that I have provided a simple and efficient starter mechanism which is provided with a plurality of independently operable starter units adapted to be operated in relays or in successive order in the starting of an attached motor, as it may be desired to use more than one starter unit in the starting operation. It is also evident that the starter unit springs, or those which have spent their energy in starting the motor, are rewound in unison by the motor, when the latter is running, without any attention on the part of the operator.

I wish it understood that my invention is not limited to any specific construction or arrangement of the parts except in so far as such limitations are specified in the claims.

Having thus described my invention, what I claim as new, and desire to secure by Letters Patent, is,—

1. A starter of the class described, having a plurality of independently operable starter units, mechanism operable to release the starter units in predetermined order, and means automatically operable to restore energy in the released units.

2. In a starter of the class described, a sectional shaft, means operable to connect the shaft sections, a plurality of independently operable starter units carried by one of said sections, and mechanism operable to move said means to connect the shaft sec-

tions and to release the starter units in predetermined order, the shaft sections being connected when a starter unit is released.

3. In a starter of the class described, a shaft, spring starting means carried by the shaft and adapted to have driving clutch-engagement therewith when released, a catch member normally coacting with a part of said means to prevent a shaft starting movement thereof, a trip-shaft having connection with said catch member and operable at a predetermined point in a rotation thereof to move the catch member to released position, and mechanism operable to impart rotary movements to said trip-shaft.

4. In a starter of the class described, a shaft, a plurality of spring actuated starter units for the shaft, a catch member associated with each starter unit for holding it against shaft driving movements, a trip-shaft common to all of said units and having a spur projecting therefrom for each unit, means attached to the catch member of each unit and movable by the respective shaft spur to move the catch member to released position at a predetermined point in a revolution of the trip-shaft, and mechanism for rotating the trip shaft.

5. In a starter of the class described, a motor shaft, a plurality of spring starter units carried by the shaft and normally held against shaft driving movements, a trip-shaft common to said units, connection between the trip-shaft and each unit operable to release the associated unit at a predetermined point in each revolution of the trip-shaft, the different units being released at different points in a rotation of the trip-shaft, and mechanism operable to impart partial turning movements to said trip-shaft.

6. In a starter of the class described, a coiled starter spring, a rotatable member attached to the outer end of said spring and adapted when rotated to rewind the spring, a rewinding shaft, driving connection between said rewinding shaft and member having a clutch means between said rewinding shaft and rotatable member, means operable to move said clutch means to close the driving connection between said shaft and member, a part carried by said member and automatically operable to move said means to clutch releasing position when the unit spring has been wound a predetermined extent.

7. In a starter of the class described, a coiled starter spring, a member attached to said spring and movable to rewind the same when its energy is spent, a spring part carried by said member and movable from normal position by an unwinding of the spring, mechanism operable to impart spring rewinding movements to said member and having clutch means for making

- and breaking the driving connection between said member and mechanism, said clutch means normally standing in engaged position and means operable by said spring 5 part at a predetermined point in a rewinding of the spring to effect a release of said clutch means to stop the spring rewinding action.
8. In an apparatus of the class described, 10 a starter spring, a rotatable element attached to said spring and movable to rewind the same, a rewinding mechanism normally in driving connection with said member to rotate the same, and means automatically 15 operable to break the driving connection with said mechanism and member when the spring has been contracted a predetermined extent upon a rewinding thereof, said means being automatically released by the unwinding 20 action of the spring to operatively connect said mechanism and member.
9. In an apparatus of the class described, 25 a plurality of shaft driving units, each having a coiled shaft driving spring, a member attached to the spring and rotatable to impart rewinding movements thereto, a rewinding mechanism common to all of said units and having parts normally in driving connection with the respective members, and 30 means automatically operable to disconnect the driving connection between said mechanism and each member when the respective springs have been rewound a predetermined extent.
- 35 10. In an apparatus of the class described, a sectional motor shaft, means movable to connect the shaft sections to rotate together, a starter spring carried by one of said sections, a member attached to said spring and 40 rotatable to rewind the same, a rewinding mechanism normally having driving connection with said member to impart rewinding movements thereto, means for holding the said member when the spring is wound to 45 a predetermined extent, means automatically operable to release the driving connection between said mechanism and member when the spring has been wound a predetermined extent, said mechanism being driven 50 from one of said shaft sections and being disconnected therefrom when the shaft sections are connected.
11. In an apparatus of the class described, 55 a motor shaft, a spring driving means for said shaft having a rotatable spring rewinding member, an eccentric driven by said shaft, a mechanism driven by said eccentric for rewinding the said spring, and a clutch for connecting the mechanism with the member.
12. In an apparatus of the class described, 60 a motor shaft, a spring starting means therefor having a spring and a spring rewinding part, rewinding mechanism in automatically operated clutch controlled connection with said part, said mechanism having a shaft, a ratchet connected to said mechanism for imparting intermittent movements thereto, and an eccentric connected to the motor shaft and to said ratchet 65 through said last named shaft for imparting movements thereto.
13. In an apparatus of the class described, 70 a shaft, a coiled starter spring for said shaft, a rotatable rewinding part attached to the spring, mechanism operable to rotate said part in spring rewinding direction, and means operable by the expansion of the spring upon the unwinding movement thereof to throw said mechanism into driving 75 connection with said part.
14. In an apparatus of the class described, 80 a shaft, a coiled starter spring for said shaft, a rotatable rewinding part attached to the spring, mechanism operable to rotate said part in spring rewinding direction, and means operable by an expansion of said spring upon an unwinding movement thereof to throw said mechanism into driving connection with said part and operable to 85 disconnect said mechanism and part at a predetermined point in a rewinding of the spring.
- In testimony whereof, I have hereunto signed my name to this specification in the 90 presence of two subscribing witnesses.
